CLAIM

The ornamental design for a tablet stand as shown and described.

DESCRIPTION

FIG. 1 is a first perspective view of a tablet stand in an extended position;

FIG. 2 is a second perspective view thereof;

FIG. 3 is a front side view thereof;

FIG. 4 is a rear side view thereof;

FIG. 5 is a right side view thereof;

FIG. 6 is a left side view thereof;

FIG. 7 is a top side view thereof; and

FIG. 8 is a bottom side view thereof.

FIG. 9 is a first perspective view of a tablet stand in a retracted position;

FIG. 10 is a second perspective view thereof;

FIG. 11 is a front side view thereof;

FIG. 12 is a rear side view thereof;

FIG. 13 is a right side view thereof;

FIG. 14 is a left side view thereof;

FIG. 15 is a top side view thereof; and

FIG. 16 is a bottom side view thereof.

FIG. 17 is a first perspective view of a tablet stand supporting a tablet;

FIG. 18 is a second perspective view thereof;

FIG. 19 is a front side view thereof;

FIG. 20 is a rear side view thereof;

FIG. 21 is a right side view thereof;

FIG. 22 is a left side view thereof;

FIG. 23 is a top side view thereof; and

FIG. 24 is a bottom side view thereof.

The broken lines shown in the drawings represent portions of the tablet stand or tablet that form no part of the claimed design.
